ADJUSTABLE MOUTHPIECE GUIDE CONTROL FOR MICROSURGICAL PROCEDURES

Eugene H. Holly, 3701 Broadway,
West Palm Beach, Fla. 33407

Filed June 28, 1974, Ser. No. 484,147

Term of patent 7 years

Int. Cl. D16—99; D24—99
U.S. Cl. D57—1 E

FIG. 1

FIG. 2

FIG. 1 is a top perspective view of an adjustable mouthpiece guide control for microsurgical procedures showing my new design; and

FIG. 2 is a bottom perspective view thereof.

I claim:

The ornamental design for an adjustable mouthpiece guide control for microsurgical procedures, as shown and described.
